(57) **CLAIM**

The ornamental design for night vision goggles as shown and described.

DESCRIPTION

FIG. 1 is a front, right, and top perspective view of night vision goggles showing my new design;

FIG. 2 is a rear, left, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged portion view taken from encircled portion, labeled “9,” in FIG. 1; and,

FIG. 10 is an enlarged portion view taken from encircled portion, labeled “10,” in FIG. 2.

The dashed-dot lines form the boundary of the enlarged portion views of FIGS. 9 and 10 in FIGS. 1, 2, 9 and 10 and form no part of the claimed design. The even dashed broken lines shown in the drawings are included for the purpose of illustrating portions of the night vision goggles that form no part of the claimed design.
